MOTOR VEHICLE PASSENGER RESTRAINT DEVICE

Harold G. Brilmyer, Grosse Pointe, and Samuel A. Heap,
Taylor Township, Wayne County, Mich., assignors to
Ford Motor Company, Dearborn, Mich., a corporation
of Delaware

Filed Nov. 20, 1967, Ser. No. 9,460

Term of patent 14 years

(Cl. D14—6)

FIGURE 1 is a front perspective view of a motor vehicle passenger restraint device according to our new design;

FIGURE 2 is a rear perspective view of the motor vehicle passenger restraint device of FIGURE 1; and

FIGURE 3 is a side perspective view of the motor vehicle passenger restraint device of FIGURES 1 and 2.

We claim:

The ornamental design for a motor vehicle passenger restraint device, substantially as shown.
